Primary Examiner — Carol P Rademaker(74) Attorney, Agent, or Firm — McAndrews, Held & Malloy, Ltd.(57) CLAIM

The ornamental design for a comestible dispenser, as shown and described.

DESCRIPTION

FIG. 1 is top, front, left side perspective view of a comestible dispenser showing my new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken line shown on the bottom surface in the FIG. 6 drawing view is included for the purpose of illustrating environmental structure and forms no part of the claimed design.
